**FLEXIBLE WEIGHT LINE AND METHOD OF
MAKING WEIGHT LINE**

Lothar J. Herzog, Burnaby, British Columbia, Canada,
assignor, by mesne assignments, to Grace Fibres Can-

ada Ltd., Brantford, Ontario, Canada
Filed May 18, 1966, Ser. No. 551,135
7 Claims. (Cl. 87—6)

ABSTRACT OF THE DISCLOSURE

A flexible weighted line comprising a core of short sections of lead, an inner braided jacket holding the lead sections, straight yarns of limited stretchability surrounding the inner braided jacket and an outer braided jacket surrounding the straight yarns.

This invention relates to flexible weight lines and to methods of making these lines.

Some types of fish nets operate in a substantially vertical plane. These nets have floats connected to upper edges thereof and weights attached to the lower edges. Some nets have individual weights connected to their lower edges, while others have lines formed of lead alone or formed with lead cores encased in plastic materials, or braided jackets. The individual weights on nets are troublesome to handle when the nets are drawn in or paid out, and they keep coming off the nets and so are lost. The lead lines whether encased or not are troublesome since they are much too stiff, and are difficult to handle, to pull over drums or rollers, and it is practically impossible to coil them or wind them on drums.

The present invention overcomes these difficulties by providing a weight line which is extremely flexible and yet has sufficient weight for its purpose. This highly flexible line is so constructed that the stretch thereof is kept at a minimum and, in fact, the stretch can be regulated within reasonable limits to a desired degree.

A flexible weight line according to this invention includes a metal core formed in short sections generally in axial alignment. An inner jacket formed of flexible material, usually a suitable rope-making material, fits around this core and holds said sections in position near each other. A layer of strong straight and flexible strands of a predetermined stretchability and size surrounds the inner jacket and extends axially of the line, said strands being free to move relative to each other. An outer jacket formed of flexible material, usually a suitable rope-making material, fits around the strand layer to hold said layer in position on the inner jacket. The metal core can be made as heavy as desired since the short sections thereof are such that the core does not interfere with the flexibility of the line. The inner jacket holds the metal core sections in their proper positions relative to each other. It is preferable to braid the inner jacket so that it is extremely flexible. The long straight strands are flexible and separated from each other so that relative movement can take place between these strands. As the strands extend axially of the line and are co-axial with the core thereof, they determine the stretchability of the line, this depending upon the material from which the strands are made. Furthermore, the strength of the line is regulated by the number and size or denier of these strands. These strands are located close to the longitudinal axis of the line so that they do not interfere with the flexibility thereof. The outer jacket also is preferably braided so that it is extremely flexible, and yet it is tight enough to hold the strands in their proper positions. In addition, the braided outer jacket provides a good grip for the hanging twines of a

2

fish net. These twines are used to attach the net to the lead or weight line. The comparatively soft and uneven outer surface of the braided jacket prevents the twines from slipping longitudinally of the weight line.

Any suitable material may be used in the jackets and the strands. For example, polyamide, polyester, polypropylene, glass fibres and the like are very satisfactory for the jackets. Yarns of these materials are suitable for use as the strands. Polyamide has considerable stretch, while polyester has very little stretch. It is necessary to control the stretchability of the weight line since a line with too much stretch in it would allow the fish net to which it is attached to be distorted, whereas a line with no stretchability might under some circumstances cause damage to the net.

It is preferable to use lead wire as the metal core since the specific gravity of lead is high, it is easily worked and readily available.

The method according to the present invention comprises partially severing a metal wire core at closely spaced intervals, along the length thereof to form interconnected short sections, and forming an inner jacket of suitable flexible material around said core. The core in its jacket is bent to sever the core sections from each other, said inner jacket being tight enough to maintain the core sections in general axial alignment. A layer of strong straight and flexible strands of a predetermined stretchability and size is formed around the inner jacket and extends axially of the line. These strands are free move relative to each other. An outer jacket of suitable flexible material is formed around the strand layer to hold said layer in position on the inner jacket. The inner and outer jackets are usually formed of a suitable rope-making material, and it is preferable to braid them so that they can be made to hold the core sections and the strands in their proper positions without interfering with the flexibility of the line. As stated above, the jackets can be made of polyamide, polyester, polypropylene, glass fibres and the like, and the filaments can be made of yarns formed of these materials. It is preferable to make the core of lead wire since this can be nipped at closely spaced intervals so that when it is flexed back and forth, the sections break away from each other. This severing of the core sections can be quickly and easily done.

It is preferable to braid the inner jacket around the metal wire core, flex the core and jacket to separate the sections of the core, and then to apply the layer of strands or yarns to the inner jacket as the latter is fed into a braiding machine where the outer jacket is braided around these elements.

An example of a weight line made in accordance with this invention is illustrated in the accompanying drawings, in which,

FIGURE 1 illustrates a metal core with an inner jacket braided thereon,

FIGURE 2 illustrates a flexible weight line, showing each of the elements forming this line,

FIGURE 3 is an enlarged diagrammatic longitudinal section through a portion of a weight line, and

FIGURE 4 is a diagrammatic illustration of apparatus for bending the metal core to separate the sections thereof.

Referring to the drawings, 10 is a flexible weight line comprising a metal, usually lead, wire core 12 which has been nipped or partially severed at closely spaced intervals 13 forming therebetween short interconnected sections 16. An inner jacket 18, usually braided, is formed around core wire 12. This jacket is usually made fairly tight around the core wire.

The inner jacket and core are flexed back and forth in any suitable manner in order to separate sections 16 from each other. For example, the jacketed core can be wound

back and forth a number of times over a pair of parallel and spaced rotating shafts 21 and 22, see FIGURE 4. This separates the core sections 16 from each other, while jacket 18 holds them generally in axial alignment, as shown in FIGURE 3.

After this operation, a layer of strong straight strands or yarns 25 is applied to the outer surface of inner jacket 18, arranged around said jacket. The strands or yarns preferably completely surround the inner jacket, but they may be spaced apart at intervals therearound. These strands or yarns extend axially of core 12, and the number of these strands or yarns, and the size or denier thereof, depends upon the strength required in the finished weight wire. These strands or yarns mainly carry any tensile load applied to the line. At the same time or immediately after, an outer jacket 28 is formed around the layer of strands 25. This jacket is preferably braided over the strands or yarns.

It will be readily recognized that although the finished weight line 32 of FIGURE 3 has a metal core, usually lead, and is relatively heavy, it is extremely flexible. The core sections 16 are very short as compared to the diameter of the weight line so that the core does not interfere with the flexibility of the line. This line can be held in a hand and shaken back and forth, and it is as supple as anything can be. Inner jacket 18 and outer jacket 28, being braided, are extensible and very flexible. The strands or yarns 25 extend longitudinally or axially of the weight line, are free to move relative to each other and are quite close to the longitudinal axis of the line so that they do not interfere with the flexibility thereof. These strands or yarns, however, determine the strength and the stretchability of the line. These strands or yarns take substantially the entire tensile load applied to the line since the inner and outer jackets are quite extensible, and the core is in separated sections. The stretchability of the strands or yarns 25 depends upon the material forming them since they are straight and extend axially of the line.

Outer jacket 28, being braided, has a comparatively soft and rough or uneven surface so that hanging twines tied around the weight line cannot slip longitudinally thereof.

What I claim as my invention is:

1. A highly flexible weight line comprising a metal core formed in short sections generally in axial alignment, an inner jacket formed of rope-making material fitting around said core and holding said sections in position near each other, a layer of strong straight yarns of a predetermined stretchability and size surrounding the inner jacket and extending axially of the line, said yarns being free to move relative to each other, and an outer jacket formed of rope-making material fitting around the yarn layer to hold said layer in position on the inner jacket.

2. A weight line as claimed in claim 1 in which both the inner jacket and the outer jacket are braided.

3. A weight line as claimed in claim 1 in which said inner jacket holds said core sections in position near each other.

4. A weight line as claimed in claim 1 in which the core is formed of lead.

5. The method of making highly flexible weight lines which comprises partially severing a metal wire core at closely spaced intervals along the length thereof to form interconnected short sections, forming an inner jacket of rope-making material around the wire core, bending the wire core and jacket to sever the core sections from each other, said inner jacket being tight enough to maintain the core sections in general axial alignment, forming a layer of strong straight yarns of a predetermined stretchability and size around the inner jacket and extending axially of the line, said yarns being free to move relative to each other, and forming an outer jacket of rope-making material around the yarn layer to hold said layer in position on the inner jacket.

6. The method of making highly flexible weight lines which comprises partially severing a metal wire core at closely spaced intervals along the length thereof to form interconnected short sections, braiding an inner jacket of rope-making material around the wire core, bending the wire core and jacket to sever the core sections from each other, said inner jacket being tight enough to maintain the core sections in general axial alignment, forming a layer of strong straight yarns of a predetermined stretchability and size around the inner jacket and extending axially of the line, said yarns being free to move relative to each other, and braiding an outer jacket of rope-making material around the yarn layer to hold said layer in position on the inner jacket.

7. The method of making highly flexible weight lines which comprises partially severing a lead wire core at closely spaced intervals along the length thereof to form interconnected short sections, braiding an inner jacket of flexible material around the wire core, bending the wire core and jacket to sever the core sections from each other, said inner jacket being tight enough to maintain the core sections in general axial alignment forming a layer of strong straight and flexible strands of a predetermined stretchability and size around the inner jacket and extending axially of the line, said strands being free to move relative to each other, and braiding an outer jacket of flexible material around the strand layer to hold said layer in position on the inner jacket.
